VAPORIZER

Filed May 13, 1922

3 Sheets-Sheet 3

UNITED STATES PATENT OFFICE.

HARRY C. WILSON, OF DETROIT, MICHIGAN.

VAPORIZER.

Application filed May 13, 1922. Serial No. 560,856.

To all whom it may concern:

Be it known that I, HARRY C. WILSON, a citizen of the United States, residing at Detroit, in the county of Wayne and State of

Michigan, have invented a new and useful Vaporizer, of which the following is a specification.

My invention is directed to an improvement in vaporizers, designed to be interposed between the carburetor and engine, and is adapted to add a proportionately measured amount of hot air to the mixture from the carburetor.

The improved construction is designed to be mechanically controlled in order to determine the amount of hot air admitted to the mixture, this control, in addition to being coincident with the movement of the throttle valve, is also designed to be governed coincidentally with an independent locking valve control.

This dual control of the vaporizer, provides positive selective proportioning of the hot air to the mixture under all operating conditions of the vehicle.

The control of the vaporizer through and in accordance with the valve lock, is an essentially important detail of the present invention, as thereby, for example, in starting a cold motor, the vaporizer may be cut off from the mixture by the independent valve control, and locked out of action and this without interfering with the movement of the throttle valve.

Thus the vaporizer may be maintained out of action, until the motor is warm, whereupon the vaporizer is unlocked, and released for its subsequent control by the throttle valve lever.

The invention, in the preferred form of details, will be described in the following specification, reference being had therein to the accompanying drawings, in which:

Fig. 1 is a perspective view, illustrating the application of the improved vaporizer, attached to the engine.

Fig. 2 is an end elevation of the same partly in section, illustrating the valve closed at advanced position of the carburetor lever.

Fig. 3 is an end elevation of the same

partly in section, illustrating the hot air distributing chamber, also the valve entirely open with carburetor lever advanced to the usual driving position.

Fig. 4 is an end elevation of the same partly in section, illustrating the valve closed at retard position of the carburetor lever, also illustrating the independent valve locking control.

Fig. 5 is a perspective view of the heating member.

Fig. 6 is a vertical longitudinal sectional view through the device assembled.

Fig. 7 is a section on line 7-7 of Fig. 5. 65

Fig. 8 is a view of the operating member of the independent locking valve control. Similar numerals refer to similar parts throughout the several views.

The improved vaporizer includes generally a means for collecting heated air and distributing the same to the mixture in the inlet manifold; the valve for the control of the heated air being dually controlled by the usual rod for operating the throttle valve, such rod being governed by the usual lever, and independent valve operating rod member.

In the particular and preferred form of details, the vaporizer comprises what might be termed a heating element 1, preferably in the form of a substantially quadrangular shell, the contact side 2 of which is adapted to be held in close contact with the exhaust pipe 3 of the engine. 80

The ears 4 at the lower part of the heater are designed for, and suitably located, so that with them, the heater may be clamped to the exhaust pipe 3, with the engine clamps 5.

The discs 6, being equal in thickness to the ears 4, permit the clamps 5 to press evenly and equally on each end. The grooved side 7, of the heater is formed into a continuous groove, starting at the end opening 8, and running back and forth from end to end to the exit 9. When the plate 10, is riveted to the side 7, with the rivets 11, the grooved member and plate become in fact a continuous pipe line, running 95 from the opening 8, to the exit 9. 100

The pipe thus arranged carries the air

back and forth from the inlet opening 8 to the exit 9 and as the heating member gets very hot from its close contact with the exhaust pipe 3 the air gets very hot, which is 5 the object of this particular arrangement of the groove or pipe.

The heating element, which will be hereinafter termed a stove, is connected through a flexible pipe 12, with a hot air control 10 and distributing member, illustrated more particularly in Figs. 2 and 4 inclusive. The pipe being connected with the distributing member at the pipe socket 13.

The distributing member comprises a metallic section 14, adapted to be secured in the inlet manifold 15, between the carburetor 16 and the engine.

This section 14 is secured to flanges 17, of the divided inlet manifold, as by bolts 18, 20 through the bolt holes 19, in metallic section 14. Thus connected, the passage 20, is in alignment with the passage of the inlet manifold, both passages being of the same size.

Section 14 is formed with a bore of three 25 different diameters 21, 22, and 23 so that when the removable annular flanged bushing 24, is fitted in place at the largest diameter of both, an annular channel 25 is formed. The removable annular bushing 24 being slightly shorter than the depth of bore 22, there is thereby provided a narrow annular slit 26, providing communication between the channel 25 and the passage 20 throughout the full annular extent 35 of the channel.

Section 14 is further formed with a horizontal bore 27, communicating with the channel 25 through the bore 28.

The bore 28 is controlled by a valve member 40 of piston form as 29, slidably mounted in bore 27, integral with the tube extension bore 30. The valve piston 29 is directly actuated by a right angled push rod 31, the rod being slidably parallel with the valve piston 29 and mounted in bearings 32 and 33, and connected with the valve piston through the bore 34.

The operative member of the piston valve 50 is the adjustable presser foot 35, mounted on the push rod 31 and adjustably secured thereto by the set screw 36. The push rod 31 extends sufficiently beyond the bearing 33 so that a spring 37 may be coiled about the rod, and held securely there by the nut 38 which is threaded on the rod.

The spring bearing as it does against the shoulder of the push rod bearing 33 and the nut 38, serves to operatively move the valve piston in one direction, the valve however is governed when desired by the movement of the carburetor lever 39, this lever being indirectly connected to the gasoline throttle by the rod 40, this being one of the dual controls of the valve piston.

60 The proportional admission of heated air

to the mixture is of course determined by the position of the piston valve 29, and the desired control of this valve in accordance with and in proportion to the movement of the usual throttle valve is provided for, by arranging the presser foot 35 on the push rod 31, as thereby for example, to correctly arrange the presser foot 35, the independent valve operating rod member 41 is turned by the ring end of same 42 so that the end actuating the piston valve 29 will be positioned as shown in Fig. 4.

The piston valve 29 being of a sufficiently large diameter at 44, closes the valve and prevents the heated air from passing through 80 the bore 28, the valve at the same time being locked closed, resulting from the position of the rod 41, thus as the point of pressure of the rod at 43 with the push rod 31 is below the centre of the rods bearing in the bore 85 45, it will thus be seen that the push of the spring 37 tends to keep the valve locked, closed.

Now while the valve is locked in this position, the gasoline throttle is retarded, 90 which in turn brings the carburetor lever 39 to the position shown in Fig. 4, then the presser foot 35 is slipped on the push rod 31 until the presser foot comes in contact with the lever 39, there the presser foot is secured with the set screw 36. Then the rod 41 is turned to position shown in Fig. 3, and when the gasoline throttle is advanced, the lever 39 gradually moves forward, the presser foot 35 follows, being forced by the 95 spring 37, thus Fig. 3 shows the piston valve 29 fully open as the diameter of the piston valve is smaller at 46 opposite bore 28, thus the heated air passes through the opening thus made by the smaller diameter, and goes on through bore 28, to channel 25, then through the slit 26, to the passage 20.

When it is desired that the car spring forward quickly, the gasoline throttle is quite far advanced, then the lever 39 moves 105 to the position shown in Fig. 2, the presser foot 35 follows until it can go no further, being stopped by the push rod 31 coming into contact with the side of the bearing of the rod 41 at 47.

The piston valve 29 being sufficiently large at 48, opposite bore 28, the valve thus is closed and the heated air cannot enter into the bore 28. The valve piston formed as it is and arranged relatively thus, automatic control of the vaporizer is thereby provided under the usual running conditions of the vehicle.

It is important, however, that the valve be controlled under other conditions than that dependent upon the operation of the throttle valve. For example, under some conditions, as in starting the cold motor, it is necessary to have a rich mixture, at all 125 positions of the throttle valve for the ini- 130

tial starting, under these conditions, as well as others, the stove is not furnishing heated air, and it is desirable that little if any air be added to the mixture; therefore the valve must be capable of control to meet these conditions, and for this purpose there is provided the additional vaporizer valve control through the rod 41 as shown particularly in Figs. 1 and 4.

10 Therefore, under conditions noted, as for example in starting a cold motor, by turning the rod 41 to the position shown in Fig. 4, the vaporizer valve is closed and locked, thus the flow of air to the mixture being entirely cut off and this without regard to any position of the throttle lever.

Therefore, under any adverse conditions, the vaporized valve may be effectively controlled by the rod 41, as well as by the 20 throttle lever, and thus the driver has within his power and judgement, the effective government of the air admission to the mixture without necessarily limiting his ordinary control of the vehicle.

25 The rod 41 is provided with a securing metal bracket 48, shown in Figs. 1 and 8, this bracket when attached with a screw to the under edge of the instrument board 49', holds the rod in a practically straight 30 line from the instrument board to the vaporizer. The rod is made folding so that it may be more conveniently packed for shipment, it is secured at the folding joints with the pins 49 and 50, the U shaped bend 51 in the 35 rod is designed as an adjustment, to either slightly lengthen or shorten the rod, which can be done with a pair of pliers.

The heated air from the stove is admitted to the inlet manifold through a narrow slit, 40 as 26 which extends all the way around the passage 20, there is therefore provided a means for thoroughly mixing the heated air with the gasoline vapor, in order to more effectively vaporize the latter.

45 Fig. 6 illustrates the direction the heated air takes on its way to the passage 20, the large arrows indicating the mixture on its way from the carburetor, in order to enter the intake manifold the mixture must 50 pass the narrow slit 26 through which the heated air enters the passage 20.

The bore of three different diameters in section 14 as well as the removable annular flanged bushing 24 are especially designed 55 thus, first so that when the same are fitted together the annular channel 25 and slit 26 is formed, and second, so that the channel and slit may result, by simply moulding section 14, and bushing 24 in this way, no 60 machining is necessary, which reduces the cost of manufacture considerably.

Having thus described the invention, what I claim as new is:

65 1. The combination with a gas engine having an intake manifold, a carburetor and

mechanism for controlling the same, of an auxiliary air supply means; and means disconnected from said controlling mechanism and cooperating therewith for controlling solely said supply means.

70 2. The combination with a gas engine having an intake manifold, a carburetor and mechanism for controlling the same, of an auxiliary air supply means; and means disconnected from and operable by, synchronously with, said control mechanism for controlling solely said supply means.

75 3. The combination with a gas engine having an intake manifold, a carburetor and control mechanism for operating the same, of an auxiliary air supply means; means for controlling the flow of air through said supply means; and means disconnected from and operable by said control mechanism for actuating solely said controlling means.

80 4. The combination with a gas engine having an intake manifold, a carburetor and control mechanism for operating the same, of an auxiliary air supply means; means for controlling the flow of air through said supply means; means disconnected from and operable by said control mechanism for actuating said controlling means; and additional means for manually actuating said controlling means.

85 5. The combination with a gas engine having an intake manifold, a carburetor and control mechanism for operating the same, of an auxiliary air supply means; means for controlling the flow of air through said supply means; and means disconnected from and operable by said control mechanism, upon the opening of the same beyond a predetermined point, for actuating said controlling means.

90 6. In combination with a gas engine having an intake manifold, a carburetor and control mechanism for operating the same, an auxiliary air supply means; and means, disconnected from said control mechanism, for opening said control means upon the opening of said control mechanism beyond a predetermined point and for closing the same upon the further opening of said control mechanism beyond a predetermined point.

95 7. The combination with a gas engine having an intake manifold, a carburetor and control mechanism for operating the same, of an auxiliary air supply means; and a pair of means for controlling the flow of air through said supply means, one of said control means being manually operable and the other being disconnected from and operable by said control mechanism.

100 8. The combination with a gas engine having an intake member, a carburetor and control mechanism for operating the same, of a fuel vaporizer having an air conduit therein; means for opening and closing

solely said conduit, said means being disconnected from and operable by said control mechanism.

9. In a fuel vaporizer having an air conduit, means controlling the flow of fuel through said conduit; means for operating said control means in relation to the operation of the control mechanism of a carburetor with which used; and additional means for operating said control means, said additional means being independent of and disconnected from said first mentioned operating means.

10. In a fuel vaporizer having an air conduit therein, a sliding valve for controlling the flow of fluid therethrough; means cooperating with the operating lever of a carburetor with which used for moving said valve in one direction, said means being disconnected from said lever; and means for automatically moving said valve in the opposite direction.

11. In a fuel vaporizer having an air conduit, means for opening and closing said conduit; means adapted for frictional engagement with the control mechanism of a carburetor with which used for operating said opening and closing means upon the operating of said control mechanism beyond

a predetermined point; and means for maintaining operating means in said engagement during certain positions of said control mechanism.

12. In a fuel vaporizer having an air conduit, means for controlling the flow of air therethrough; thrust receiving means disconnected from the carburetor with which used for operating said controlling means; and additional manually operable means for operating said controlling means.

13. In a fuel vaporizer having an air conduit, means for opening and closing said conduit to permit the passage of air therethrough; means for deflecting the said air from its path of travel; means adapted for frictional engagement with the control mechanism of a carburetor with which used for operating said opening and closing means upon the operating of said control mechanism beyond a predetermined point; and means for maintaining said operating means in said engagement during certain positions of said control mechanism.
